UNITED STATES PATENT OFFICE.

RALPH E. POWELL, OF TOLEDO, OHIO.

VENTILATOR.

1,085,758.

Specification of Letters Patent.

Patented Feb. 3, 1914.

Application filed March 1, 1913. Serial No. 751,480.

To all whom it may concern:

Be it known that I, RALPH E. POWELL, a citizen of the United States, and a resident of Toledo, in the county of Lucas and State of Ohio, have invented a certain new and useful Ventilator; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates particularly to window ventilators, but is *not* restricted to such use; and has for its object the provision of an improved ventilator of this character, which is simple and inexpensive in its construction, easy and rapid to install, and capable of being regulated to control the air flow therethrough.

A further object of my invention is to construct a ventilator of this character in such manner that it will coöperate with the wind when blowing at an oblique angle thereagainst to cause a circulation of air within the associated room, the air being caused to enter the room through one portion of the ventilator and to have its exit therefrom through another portion of the ventilator.

The invention is fully described in the following specification, and while, in its broader aspect, it is capable of embodiment in numerous forms, a preferred embodiment thereof is illustrated in the accompanying drawings, in which,—

Figure 1 is an inner side elevation of a ventilator embodying the invention with a part broken away. Fig. 2 is an edge view thereof with portions broken away. Fig. 3 is a side elevation of one of the damper members, and Fig. 4 is a perspective view of one of the end or filler blocks.

Referring to the drawings, 1 and 2 designate inner and outer side strips, respectively, of sheet metal or other suitable material, which are spaced apart by and secured at their upper and lower edges to upper and lower frame strips 3 and 4. The sides 1 and 2 and top and bottom frame strips of the ventilator thus coöperate to form an inner compartment, which is preferably divided into the compartments 5 and 6 by a partition member 7 which is disposed within the ven-

tilator at substantially the center thereof. The side strips 1 and 2 have deflecting tongues or fins 8 struck inwardly therefrom to form vertically elongated air inlet openings 9 for each compartment with the tongues of the two compartments obliquely disposed relative to the side walls and projecting in opposite directions. In the present instance, the tongues of each compartment project toward the outer end thereof and the openings 9, which are formed thereby, are preferably disposed in staggered relation with respect to the opposite sides so that the tongues 8 of one side alternate with the tongues 8 of the other side.

The arranging of the tongues 8 for the different compartments in the manner shown, that is, with the tongues of the two compartments projecting in opposite directions and in oblique planes relative to the side walls of the ventilator is quite an important feature of the invention as a more perfect circulation of the air within an associated room is thereby occasioned than would otherwise be the case, providing the wind is blowing in a direction which is oblique to the outer side of the ventilator, rather than directly against the same at right angles thereto. For instance, should the wind be blowing against the outer side of the ventilator in an oblique direction, as indicated by the arrows *a* it will strike against the tongues or flanges 8 which stand across the path of movement thereof and will be deflected outwardly thereby instead of passing through the ventilator, thus creating a suction through the compartment 6 and effecting an outward drawing of the air therethrough from within the room. The portion of the wind which strikes the outer side of the other compartment passes therethrough and into the adjoining room due to the flanges 8 of the outer side being disposed in the direction of movement of the wind. It is thus evident that the air within the room will be more rapidly and effectually changed than would be possible if the wind entered through both compartments of the ventilator as the wind in coaction with the ventilator effects a forced draft within the room, the fresh air entering the room through one portion of the ventilator and having its exit therefrom through another portion of the ventilator.

In order to enable the inner openings 9 of the ventilator to be partially or completely

closed, as it may be desired to reduce or completely stop the passage of air through the ventilator, each compartment is provided with a shutter or damper member 10, 5 which is provided with spaced shutter parts 10^a that are adapted to lie flat against the inner side of the portions of the side 1 of the ventilator disposed between the openings 9 and to be moved by a longitudinal 10 movement of the shutter into position to close or partially close said opening as desired. The upper and lower edges of the shutter 10 work in guide grooves or recesses 11 in the adjacent inner edges of the top and 15 bottom frame strips 3 and 4. Each shutter 10 has a handle part 12 projecting outwardly therefrom through a registering slot 13 in the inner side 1 of the ventilator. The provision of a separate shutter member for 20 each ventilator compartment enables the openings of either compartment to be regulated as desired.

It will be understood that the ventilator is intended to be mounted within the window casing either below or above the window sash in the casing run-ways therewith, and in order to adapt the ventilator for windows of different widths the ends of the ventilator are preferably provided with 25 removable blocks 14 that may be easily dressed down, as desired, to suit the width of the window casing. These blocks seat at 30 their inner edges against the ends of the frame pieces 3 and 4 between slightly extended portions of the sides 1 and 2, which latter serve to hold the blocks against transverse movements, and pin members 15 project laterally from each end of the blocks and are intended to seat in grooves 16 in 35 the outer sides of the respective end portions of the top and bottom frame members 3 and 4 of the ventilator to assist in holding the blocks in position. The pins 15 may be in the nature of spring fingers, which, in 40 addition to seating in grooves 16, are adapted to yieldingly grip the end portions of the ventilator to hold the blocks 14 thereto.

I wish it understood that my invention

is not limited to any specific construction or arrangement of the parts except in so far as such limitations are specified in the claims.

Having thus described my invention, what I claim as new, and desire to secure by Letters Patent, is,—

1. A ventilator of the class described having separate compartments each provided with a plurality of air passages therethrough, and a plurality of deflecting fins associated with said passages with the fins of the different compartments projecting in opposite directions and in oblique planes relative to the ventilator sides.

2. A ventilator of the class described having spaced side portions each provided with a plurality of openings and having obliquely disposed deflecting fins projecting inwardly from adjacent to said openings.

3. A ventilator of the class described having inner and outer side walls provided with openings therethrough, and obliquely disposed deflecting fins projecting inwardly and in the same direction from the side walls.

4. A ventilator of the class described having openings therethrough, obliquely disposed deflecting fins projecting inwardly from a side of said openings, and a shutter member movable to open or close said openings.

5. A ventilator of the class described having separate compartments therein and provided with air passages transversely therethrough each compartment having inwardly projecting deflecting fins, and a shutter disposed within each compartment and operable to open or close the air passages therethrough.

In testimony whereof, I have hereunto signed my name to this specification in the presence of two subscribing witnesses.

RALPH E. POWELL.
